UNITED STATES PATENT OFFICE.

EDMUND F. GEBHARDT, OF EASTON, PENNSYLVANIA.

RELIEF-VALVE.

1,138,551.

Specification of Letters Patent.

Patented May 4, 1915.

Application filed June 12, 1913. Serial No. 773,289.

To all whom it may concern:

Be it known that I, EDMUND F. GEBHARDT, a citizen of the United States, residing at Easton, in the county of Northampton and 5 State of Pennsylvania, have invented new and useful Improvements in Relief-Valves, of which the following is a specification.

This invention relates to improvements in relief valves, proposing a structure which is 10 especially applicable to hot water heating systems, wherein the relief valves are interposed between the expansion tank and a pipe leading from the boiler and serve to regulate the pressure in the system without 15 regard to the elevation of the tank.

Valve constructions of the type stated 20 usually include two valve bodies, one of which (for convenience, herein designated as the "main" valve) controls the passage through which the water flows from the system to the expansion tank, and the other of which, (for convenience, herein designated as the "return" valve) controls the passage 25 through which the water returns from the expansion tank into the system.

The present invention is essentially directed to the organization of the main or relief valve proper and its principal object 30 is to provide a relief valve, as described, wherein the parts are so organized that the main valve cannot become "stuck" upon its seat, and hence, cannot fail to open when the pressure in the system exceeds that determined upon as the maximum, yet is effectively closed during all normal ranges of the 35 pressure in the system.

A further object of the invention is to 40 provide an organization which, while having the advantage stated in the preceding sentence, is, at the same time, of simple, inexpensive, and practical character, embodies no parts which are liable to breakage, derangement, or undue wear, and is readily accessible for the purposes of cleaning, 45 renewal, or repair, whenever the occasion may require.

An embodiment of the invention is illustrated in the accompanying drawings, 50 wherein the figure is a vertical central sectional view of the improved valve.

The valve comprises a casing 1 which is connected, on the one hand, to the system by a pipe 2, and on the other hand, to the expansion tank 3 by a pipe 4. Within the casing 55 a pipe 5 is provided, which directly communicates with the pipe 2, forming, in effect,

an extension thereof, and has at its upper end an annular valve seat 6, which functions as an outlet into the interior of the casing 1 and is normally closed by a main valve 60 7. When the pressure in the system exceeds the maximum degree determined upon, the water forces the valve 7 from its seat, and then passes into the interior of the casing 1 and through the pipe 4 into the expansion 65 tank 3. When the pressure in the system falls below the maximum degree determined upon, the water flows from the expansion tank into the interior of the casing, and through the return valve 8 into the pipe 5, 70 and through this back into the system. The flow of water from the system into the expansion tank is indicated by the arrows in full lines, and the return of water from the expansion tank into the system is indicated by the arrows drawn in dotted lines. 75

The valve 8 works with relation to a seat 9, and the valve seats 6 and 9 are conveniently formed as parts of a casing or enlargement 10, provided at the upper end of 80 the pipe 5. The valve 7 is normally held closed by a weight 11, preferably in the form of a ball, and resting upon a concave upper surface 12 of said valve. The relation between the weight 11 and the valve and 85 the casing is such that no special guide means for said weight, during the opening and closing movements of the valve 7, is required. It will be observed that there is a substantial space intervening between the 90 weight and the surrounding wall of the casing 1, yet the weight is always accurately centered with relation to the valve 7, and cannot possibly become displaced or disengaged from said valve. This is due to the 95 relation between the casing 1 and the weight 11 which is so selected that while said weight normally has no contact with said casing, yet it cannot become disengaged from the valve because should it momentarily move to one 100 side of the valve during the movement of the latter, said weight cannot move in any direction beyond or as far as the center of the valve but will strike against the casing and ultimately return to its seat upon said 105 valve. The valve 7, in turn, is accurately and positively centered with relation to its seat, and for this purpose, it is preferable to make said seat 6 in the form of a flange having the outline of a truncated cone, the 110 upper edge face of said flange engaging securely against the under face 13 of the

valve 7, and the latter being provided with an annular extension 14 which projects downwardly beyond the face 13 and has its lower end fashioned as at 15 to seat upon the flat upper wall of the casing or enlargement 10. It will thus be apparent that the construction of valve and valve seat described provides for at least two pairs of coacting valve surfaces, one of which consists of the valve surface 13, and the upper edge of the seat 6, and the other of which consists of the valve surface 15, and the top wall of the casing or enlargement 10. The relation of the coöperating valve faces not only insures of the accurate and positive centering of the valve 7 with relation to its seat, as described, but it also insures of a particularly reliable closure of the valve 7, since, in the event that there should be wear between the face 13 and the seat 6, the valve 7 will still effectually close the outlet from the casing or enlargement 10, by virtue of the engagement of the valve face 15 upon the top wall of said casing or enlargement.

The casing 1 is preferably made in upper and lower sections 1^a and 1^b, and the lower section 1^b is connected to the pipes 2 and 4, while the upper section 1^a, which incloses the operating part of the valve, has its lower end threaded for engagement with corresponding threads at the upper end of the section 1^b. The section 1^a has at its upper end a projection 1^c for engagement by a wrench when it is desired to remove the section 1^a from the section 1^b. When such removal has been accomplished, the parts of the valve are readily accessible, as is obvious.

It will be apparent from the foregoing description that the valve herein described is of extremely simple structural character, and embodies no parts which are liable to derangement. The weight 11 effectually holds the valve 7 in closed relation, and the effectiveness of the closure afforded by the valve 7 is determined by the manner in which said valve is positively centered with relation to its seat, and also by the provision of at least two pairs of coacting valve faces, whereby should one pair of valve faces become somewhat worn, the other faces will give good service. While the weight 11 is particularly effective in maintaining the closed relation of the valve 7, the organization of said weight with relation to said valve and the casing is such that the valve is reliably responsive to an increase in the pressure in the system beyond the degree determined upon as a maximum, since there is no liability of the valve being stuck to its seat, and since the valve 7 and the weight 11 cannot possibly be subject to deposits of foreign matter suspended in the water, and cannot be affected by any deposits that may be precipitated upon the walls of the casings 1 or 10.

Having fully described my invention, I claim:

1. A relief valve organization comprising a casing having separate inlet and outlet connections, a pipe within said casing forming a continuation of the inlet connection and having at its upper end a valve seat which functions as an outlet into said casing, a main valve normally closing the outlet at the upper end of said pipe and being positively centered with relation to said seat, the main valve having a concave upper face, and a spherical weight resting upon the main valve and conformably seating upon said concave upper face, the width of the casing being so selected that the weight has normally no contact with the casing and displacement of said weight in any lateral direction as far as the center of said valve is prevented by the wall of the casing which surrounds said weight.

2. A relief valve organization comprising a casing having separate inlet and outlet connections, a pipe within said casing forming a continuation of the inlet connection and having at its upper end a valve seat which functions as an outlet into said casing, a main valve normally closing the outlet at the upper end of said pipe and being positively centered with relation to said seat, and a spherical weight resting upon the main valve, the width of the casing being so selected that the weight has normally no contact with the casing and displacement of said weight in any lateral direction as far as the center of said valve is prevented by the wall of the casing which surrounds the said weight.

3. A relief valve organization comprising a casing having separate inlet and outlet connections, a pipe within said casing forming a continuation of the inlet connection and having at its upper end a valve seat which functions as an outlet into said casing, a main valve normally closing the outlet at the upper end of said pipe and being positively centered with relation to said seat, and a spherical weight resting upon the main valve, the width of the casing being so selected that the weight has normally no contact with the casing and displacement of said weight in any lateral direction as far as the center of said valve is prevented by the wall of the casing which surrounds said weight, said valve seat consisting of a flange formed as a truncated cone and the said valve engaging said flange with its under face and having an extension surrounding the flange and adapted to engage upon the upper face of said pipe.

4. A relief valve organization comprising a casing having separate inlet and outlet connections, a pipe within said casing forming a continuation of the inlet connection and having at its upper end a valve seat

- which functions as an outlet into said casing, a main valve normally closing the outlet at the upper end of said pipe and being positively centered with relation to said seat, 5 the main valve having a concave upper face, and a spherical weight resting upon the main valve and conformably seating upon said concave upper face, the width of the casing being so selected that the weight has normally 10 no contact with the casing and displacement of said weight in any lateral direction as far as the center of said valve is prevented by the wall of the casing which surrounds said weight, said valve seat consisting of a flange formed as a truncated cone and the said valve engaging said flange with its under face and having an extension surrounding the flange and adapted to engage upon the upper face of said pipe. 15 5. A relief valve organization comprising a casing having separate inlet and outlet connections, a pipe within said casing form- 20
- ing a continuation of the inlet connection and having at its upper end a valve seat which functions as an outlet into said casing, 25 a main valve normally closing the outlet at the upper end of said pipe and being centered with relation to said seat, and a spherical weight acting upon the main valve to hold the latter against its seat, the width of 30 the casing being so selected that the weight has normally no contact with the casing and the displacement of said weight in any lateral direction as far as the center of said valve is prevented by the wall of the casing 35 which surrounds said weight.

In testimony whereof I have hereunto set my hand in presence of two subscribing witnesses.
